United States Patent Office

Des. 206,034
Patented Oct. 18, 1966

206,034

SEWING MACHINE, OR SIMILAR ARTICLE

Victor Reichenstein, Great Neck, N.Y., assignor to Consolidated Merchandising Corp., New York, N.Y., a corporation of New York

Filed Dec. 1, 1965, Ser. No. 9

Term of patent 7 years

(Cl. D70—1)

FIG. 1

FIG. 2

FIG. 3

FIG. 4

FIG. 1 is a side perspective view of a sewing machine showing my new design;

FIG. 2 is a rear perspective view thereof;

FIG. 3 is a side perspective view of the side opposite that shown in FIG. 1; and

FIG. 4 is a front perspective view thereof.

The essential features of my design reside in the full line disclosure on the drawing.

I claim:

The ornamental design for a sewing machine, or similar article, substantially as shown and described.
